UNITED STATES PATENT OFFICE.

ANDREW W. STEIGER, OF NEW YORK, N. Y., ASSIGNOR TO THE YOST
WRITING MACHINE COMPANY, OF NEW YORK.

TYPE-WRITING MACHINE.

SPECIFICATION forming part of Letters Patent No. 461,553, dated October 20, 1891.

Application filed May 6, 1889. Serial No. 309,683. (No model.)

To all whom it may concern:

Be it known that I, ANDREW W. STEIGER, a citizen of the United States, and a resident of New York city, in the county of New York and State of New York, have invented certain new and useful Improvements in Type-Writing Machines, of which the following is a specification.

My invention in type-writing machines has 10 for its main object to provide what is known as "straight stringing"—that is to say, a machine in which the key-levers are arranged side by side and parallel and in which the rods which connect the key-levers with the 15 type-carriers are arranged in vertical planes or perpendicular to the key-levers or the bed or base of the machine; and my invention consists in combining sub-levers with certain of the key-levers and connecting-rods, all as will 20 be hereinafter more fully described, and particularly pointed out in the appended claims.

In the drawings accompanying this specification, Figure 1 is a central vertical section of a portion of a type-writing machine embodying my invention. Fig. 2 is a plan view, partly in section, taken above the bed-plate and sub-levers to show more clearly the construction and arrangement of the parts involving my invention. Fig. 3 is a plan view 25 of one modification of my invention. Fig. 4 is a similar view of another modification. Fig. 5 is a vertical section through the bed, showing a finger-key, key-lever, and the coupling used between the key or main lever and its 30 sub-lever.

In the several views the same part will be found designated by the same letter or numeral of reference.

A denotes the paper-carriage, having, as 40 usual, a cylindrical platen B.

C is a top plate supporting an inking-pad D. E is a link or lever pivoted to the top plate.

F is another link or lever pivoted to a stand- 45 ard at the center of the bed-plate G.

H is a type bar or carrier, to which are pivoted at *a* and *b*, respectively, the links E and F. The links E extend all around the circular top plate, and in practice the machine is provided with as many such links or levers 50 as there are finger-keys and key-levers.

2 2 represent vertically-arranged connect-

ing-rods, which are disposed in a circle, as shown particularly at Figs. 2 and 3.

3 3 represent the key-levers, arranged beneath the bed plate and parallel to each other. 55

4 denotes the pivot or fulcrum of the key-lever, the outer or forward end of which is provided with a finger-key or head 5.

In the machine represented there are eighty key-levers 3 3 and eighty connecting-rods 2 2. 60 The connecting-rods being arranged in a circle and the key-levers in equidistant and parallel lines, some of the key-levers on the right and some on the left must be located in planes wholly exterior to the circle occupied by the 65 connecting-rods, for it will be seen that the connecting-rods on the right and on the left hand side of the machine occupy so nearly the same vertical longitudinal planes that it is impossible to arrange their respective key- 70 levers directly opposite or in line.

In order to connect the levers which lie outside of the series of connecting-rods with their respective connecting-rods some form of lateral offset or cross connection must be provided. For this purpose I employ a series of 75 sub-levers. Referring particularly to Figs. 1 and 2, the sub-levers designated by the numeral 6 are of different lengths and are radially arranged. The inner ends of these 80 sub-levers 6 6 are fulcrumed at 7 7 in a stand or bracket upon the bed-plate. The fulcrum ends of the sub-levers are preferably formed with round disks 8, which are set edgewise between two annular grooved plates 9 and 10, 85 the former serving as a support for the sub-lever ends and the latter as a cover therefor to prevent accidental displacement. The cover 10 is preferably secured in place by a nut 11, screwed onto a threaded shank 12, pro- 90 jecting through the centers of the plates 9 and 10. The outer ends of the sub-levers are passed through elongated eyes 13 in couplings 14, which extend vertically through the base-plate and connect at their lower ends to the 95 rear ends of those key-levers which lie outside the circle of connecting-rods. Between the ends of each sub-lever is connected, as at 15, the lower end of one connecting-rod 2, whose upper end is connected to the link or 100 lever E, as at 16. At Fig. 2 the sub-levers are made of different lengths and are radi-

ally arranged. This construction and arrangement of the sub-levers I deem preferable, and in practice the machines are made in this manner.

5 The operation will be readily understood. A depression of the finger-key 5 will elevate the rear end of the key-lever 3, which will lift the coupling 14. The coupling is guided in a hole in the bed-plate, and as it rises lifts 10 the outer end of the sub-lever 6 and vibrates it about its fulcrum or pivot, as shown by the dotted lines at Fig. 1. During the ascent of the sub-lever the connecting-rod is pushed up by it and the links E and F are vibrated in 15 opposite directions and the type c at the end of the type-carrier is brought to the printing-point and caused to make its impression on the paper on the platen. When the pressure is released, the parts return to first position 20 by gravity; but, if desired, a spring suitably located may be provided for assisting the parts back to their initial positions.

Instead of the specific type-moving devices shown, the links or levers E may be made 25 longer and provided with type, as in machines in common use.

In the modification shown at Fig. 3 the sub-levers 6 are pivoted or fulcrumed upon a common straight bar or pin 17, running longitudinally of the machine and arranged in the 30 center of the circle described by the connecting-rods. These sub-levers extend outwardly from each side of the common pivot in parallel lines beyond the series of connecting-rods. 35 The connecting-rods on the right and on the left are connected to the sub-levers after the manner illustrated at Fig. 1, and the free ends of the sub-levers are by means of vertical couplings or links 14 connected to the key-levers 3 beneath the bed-plate.

In the modification shown at Fig. 4 the sub-levers are pivoted or fulcrumed upon a common pivot 17, as in Fig. 3, but are arranged exteriorly of the circle formed by the series 45 of connecting-rods. These sub-levers are connected to the key-levers in the manner explained of the others. In Figs. 1, 2, and 3 the sub-levers are levers of the second kind or order, and in Fig. 4 the sub-levers are levers 50 of the third kind or order. In each case the sub-levers are preferably mounted or arranged above the bed or base plate.

In practice usually from ten to twenty sub-levers on each side will be required, according 55 to the diameter of the circle formed by the connecting-rods and the distance apart of the key-levers. All of the remaining key-levers, it will be observed, may run directly to their respective connecting-rods, as indicated at Figs. 2 and 3 by the parallel dotted lines, which represent the key-levers.

By my invention, the connections being made in the form of levers, (which readily turn upon their pivots or fulcrums,) the force 65 applied to the finger-keys is freely transmitted through the sub or auxiliary levers to the connecting-rods, and so easily that in the op-

eration of the machine the difference in touch between the key-levers not connected to sub-levers and those connected thereto is wholly 70 imperceptible to the operator.

What I claim as new, and desire to secure by Letters Patent, is—

1. In a type-writing machine, the combination, with type bars or carriers, of vertical 75 connecting-rods arranged in a circle, horizontally-arranged parallel key-levers extending on each side beyond the circle of vertical connecting-rods, horizontally-arranged sub-levers connected to the side connecting-rods 80 and extending laterally and connected to those key-levers which lie beyond the circle of vertical connecting-rods, substantially as set forth.

2. In a type-writing machine, the combination, with type bars or carriers, of vertical 85 connecting-rods arranged in a circle, horizontally-arranged parallel key-levers extending on each side beyond the circle of vertical connecting-rods, horizontally-arranged sub-levers fulcrumed centrally of the machine 90 and extending laterally outward on each side beyond the circle of vertical connecting-rods and connected each at one point to one of the side connecting-rods and at another point 95 to one of those key-levers which lie beyond the circle of connecting-rods, substantially as set forth.

3. In a type-writing machine, the combination, with type bars or carriers, of vertical 100 connecting-rods arranged in a circle, horizontally-arranged parallel key-levers extending on each side beyond the circle of vertical connecting-rods, horizontally-arranged sub-levers fulcrumed centrally of the machine and 105 radiating outward on each side beyond the circle of vertical connecting-rods and connected each at one point to one of the side connecting-rods and at another point by means of a vertical coupling to one of those 110 key-levers which lie beyond the circle of connecting-rods, substantially as set forth.

4. In a type-writing machine comprising a series of type-lever devices and vertical 115 thrust or connecting rods therefor, all in circular arrangement, the combination, with those connecting-rods which are at the transverse portion of their circle of arrangement, of levers suitably fulcrumed and having an engagement for a lever action with the lower 120 ends of said connecting-rods and suitably transversely extended from such engagement, and the key-levers arranged longitudinally and at desired distances apart, connecting, respectively, with said transversely-extended 125 levers.

Signed at New York city, in the county of New York and State of New York, this 15th day of December, A. D. 1888.

ANDREW W. STEIGER.
